UNITED STATES PATENT OFFICE.

EDWIN V. WHITAKER, OF GLOVERSVILLE, NEW YORK.

GLOVE.

SPECIFICATION forming part of Letters Patent No. 284,150, dated August 28, 1883.

Application filed March 30, 1883. (No model.)

To all whom it may concern:

Be it known that I, EDWIN V. WHITAKER, of Gloversville, in the county of Fulton and State of New York, have invented certain new and useful Improvements in Gloves; and I do hereby declare that the following is a full, clear, and exact description of the invention, which will enable others skilled in the art to which it appertains to make and use the same, reference being had to the accompanying drawings, which form a part of this specification, in which—

Figure 1 represents a glove provided with my improvement. Fig. 2 is an inside view of the top of the glove with its elastic web or wristband cut open, and Figs. 3 and 4 are plan views of two slightly-different ways of shaping the elastic web or wristband.

Similar letters of reference indicate corresponding parts in all the figures.

My invention has relation to gloves, and it contemplates certain improvements upon the glove for which Letters Patent were granted to me on the 23d day of August, 1881, No. 246,259; and it consists to that end in fastening a knitted wristband having a flap upon its upper edge, and the whole knitted in one piece and with a selvage, upon a glove having a slit or gore upon the usual place in button-gloves, as herein-after more fully shown and described, and particularly pointed out in the claims.

In the construction of the glove described in my former patent there has been the drawback that the wrist portion of the same was rather bulky, and that the glove had to be cut out or scalloped in a manner different to the usual shape of button-gloves, so that the knitted wristband could only be used in gloves cut especially to fit it; and to make it possible to provide a usually-shaped glove with an elastic wristband, which will obviate the necessity of buttons and take the place of a pulse-warmer at the same time, I construct the wristband as follows:

In the accompanying drawings, the letter A indicates a glove having a slit or gore, B, in the inner portion of the wrist of the glove, cut from the edge.

C is a piece of knit webbing, knit with parallel and straight upper and lower edges, and

having a flap, D, projecting from its upper edge, knit in one piece with the wristband C, all the edges of which are knit with a selvage.

The wristband is knit in a flat piece, as shown in Figs. 3 and 4, and the ends of the same are knit obliquely, as shown at E, converging toward the lower edge, so as to form a narrower opening at the lower edge, widening toward the upper edge, when the ends are united in any manner of uniting knit fabrics. This 55 wristband is stitched upon the inside of the glove by a row of stitches following the edge of the glove and the gore, the latter being covered by the flap D, so as to form a wristlet, and at the same time, by its elasticity, hold the 60 glove upon the hand without causing too great a strain or pressure around the wrist, the gore 65 B and the elastic flap D admitting of the wrist of the glove being dilated for the insertion of the hand, and the elastic flap and the elasticity 70 of the wristband drawing the glove around the wrist.

Having thus described my invention, I claim and desire to secure by Letters Patent of the United States—

1. The wristband having parallel upper and lower edges, and the edges at its ends converging toward the lower edge, as described, and having a flap projecting from the upper edge, near the one end, the whole knit with a selvage, and adapted to be stitched to the wrist portion of a usually-shaped button-glove as a new article of manufacture.

2. The combination, with the wristband having parallel upper and lower edges, the edges of its ends converging toward the lower edge, and a flap projecting from the upper edge, of a glove having the usual slit or gore at the wrist portion, the said wristband adapted to be attached to the wrist portion of the said 80 glove, as and for the purpose shown and set forth.

In testimony that I claim the foregoing as my own I have hereunto affixed my signature in presence of two witnesses.

E. V. WHITAKER.
